CLAIM

The ornamental design of the card holder, as shown and described.

DESCRIPTION

FIG. 1 is a perspective view of a card holder of my new design;

FIG. 2 is a top plan view thereof;

FIG. 3 is a side elevational view thereof, the opposite side being a mirror image thereof;

FIG. 4 is a end elevational view of the left end thereof;

FIG. 5 is a end elevational view of the right end thereof;

FIG. 6 is a bottom plan view thereof;

FIG. 7 is a perspective view of a first modification of the card holder of FIG. 1;

FIG. 8 is a top plan view of FIG. 7;

FIG. 9 is a side elevational view of FIG. 7, the opposite side being a mirror image thereof;

FIG. 10 is an end elevational view of the left end of FIG. 7;

FIG. 11 is an end elevational view of the right end of FIG. 7; and,

FIG. 12 is a bottom plan view of FIG. 7.
